No. 693,833.

Patented Feb. 25, 1902.

J. G. BUZZELL.

MACHINE FOR CONCAVING THE BREASTS OF HEELS.

(Application filed Apr. 25, 1901.)

(No Model.)

UNITED STATES PATENT OFFICE.

JOHN G. BUZZELL, OF LYNN, MASSACHUSETTS.

MACHINE FOR CONCAVING THE BREASTS OF HEELS.

SPECIFICATION forming part of Letters Patent No. 693,833, dated February 25, 1902.

Application filed April 25, 1901. Serial No. 57,409. (No model.)

To all whom it may concern:

Be it known that I, JOHN GARDNER BUZZELL, a citizen of the United States of America, and a resident of Lynn, county of Essex, 5 and State of Massachusetts, have invented certain new and useful Improvements in Shoe-Heel Top-Lift Breast-Concaving Machines, of which the following is a specification.

My invention has for its object the production of a machine to expeditiously and economically concave the bottom of the top lift of the heel of a shoe or boot, adjacent to the "breast" thereof, with great precision and nicety and with such variety of concaves as 10 may be suggested to the operator or required by the style or demands of the trade. The old or present method of performing such labor is manual and the finish dependent upon the skill and taste of the workman in cutting 15 and sandpapering, obviously producing results which are varied and undesirable in a "case" of footwear and which detracts from their salable qualities where much depends upon the finish of this class of goods. To effect the practical operation of this form of 20 ornamentation, I proceed in the manner illustrated in the annexed drawings, forming a part of this specification, in which—

Figure 1 exhibits a side elevation of the 25 front of my improved shoe-heel top-lift breast-concaving machine with a rotating cutter and a sandpapering-disk thereto attached. Fig. 2 is a plan longitudinally below the dashed line 2 2 of Fig. 1. Fig. 3 is an end elevation of the devices retaining the leather top lift in a position to be concaved. Fig. 30 4 denotes a longitudinal section of the appurtenances gaging the top lift against the rotating cutter-blades. Fig. 5 is an elevation 40 of the cutter with its shield removed. Fig. 6 is a view in perspective of the machine assembled for practical use, and Fig. 7 a perspective of the top lift attached to the heel viewed from the under side or tread to exhibit the result of the machine's finish or 45 concave.

Corresponding letters of reference denote similar features throughout the several views, referring to which—

50 A designates the head of my machine, provided with two horizontally-revoluble shafts,

the upper supporting the smoother or finisher and the lower carrying the cutter, comprising, preferably, six blades, the cutting edges of which have a defined angle to form the 55 concave in proper relation to the plane of the top lift, the assembled cutter having a protective shield covering its outer face.

Integral with the head A of the machine are two flanges A' A' and the bearing A², which 60 collectively support the curved slidable plate or work-rest B, adjusted when desired by the thumb-nut C, which traverses the screw D, secured in the machine-head, the end B' of this plate being bifurcated, so as to embrace 65 the circumferential slot in the shank of said thumb-nut. Said plate is further movably connected to the bearing A² by the screw E, (also secured in the head,) which passes through the slot B⁴ in the slidable plate, Fig. 70 2. The spring F surrounding said screw confines said plate B in a yielding manner against the bearing A², which also serves as a fulcrum for said plate B in its resistance to the spring F, the tension of which is regulated 75 by the nut G. The slidable plate thus attached to the machine-head can in the first instance be moved horizontally toward or away from the cutter by the rotation of the thumb-nut C, and in the second instance it 80 may be adjusted laterally away from or toward the machine-head by the nut G. Primarily, however, the office of said nut and screw is to hold the plate and its attached incline in engagement with the projection A³, 85 presently described.

Adjustably secured to the back of the slid- 90 able plate B by the screws H' H' passing through slots B³ B³ will be observed the incline H, which, abutting against the projec- 95 tion A³, forming an integral part of the machine-head intermediate with the flanges A' A', will force the plate end B² gradually outward whenever it is moved toward the cutter and always in a horizontal plane coincident 100 with the angle of the cutting-blade adjacent in its revolution to said slidable plate, the end of which, B², is set at a selected angle with the main body and supports rigidly the heel-rest plate I. The rearward edge of the 105 end thereof in proximity to the blades of the cutter is concaved sufficiently, as at I', to en-

croach upon its front face, and thus produce the slighter concave I^2 , which allows the material composing the heel to be cut away to a desired depth without contact of the revolving blades with the metal heel-rest I .

To confine the top lift evenly, so that the concaving will be symmetrical, duplex rocker-arms J are movably attached to the face of said plate I , near the upper and under edges thereof, by the pivotal screws K . The contiguous ends $J' J'$ are held in juxtaposition by the restraining helical spring L , against the action of which to expand said ends $J' J'$ and to decrease the space between the opposite ends $J^2 J^2$ is provided the adjustable duplex inclined finger-piece M confined in the slot N' , Fig. 1, through the intermediate plate N , secured to the plate B by the shouldered confining finger-piece M^2 , threaded in the button M' , which is loosened slightly and the finger-piece moved forward between the ends $J' J'$ of said rocker-arms until the ends $J^2 J^2$ thereof approach sufficiently to embrace or to define the contour of the top lift, the shoe being held against the rest or plate I by the hand of the operator in a position to press the top lift against the edges of the revolving blades, and thus cut the concave Q . (Exhibited in Fig. 7.) When desirable, this concave Q may be increased or diminished in length or transversely of the top lift by adjusting inwardly or outwardly the upper and lower extension-plates O , each having a lengthwise slot and screws P therethrough, by which they are confined to the front sides of the rocker-arm ends $J^2 J^2$. The reflexed ends $O' O'$ are turned inwardly and adapted to bear upon the vertical corners of the breast of the top lift to accomplish the purpose above stated. Obviously there are diverse methods (not herein illustrated) through which said rocker-arms may be oscillated, such as a right and left threaded screw, and other modifications may be suggested which will not depart from the essence of my invention and are intended to be included in the claims. In the practical cutting of these top lifts those of the smallest and uniform size are preferably first selected and concaved and in succeeding order the larger sizes. This method avoids the necessity of frequently gaging the machine and obviously expedites the work.

Having ascertained the nature and operation of my improved invention, I desire not to be held to the strict interpretation of the details of construction herein described and illustrated, but may adapt such equivalents therefor as would come within the fair scope and spirit of my invention, and I claim—

1. A machine for the purpose stated comprising a cutter-shaft mounted in suitable bearings in the frame of the machine, and a beveling cutter carried by said shaft, a work-rest mounted on said frame and comprising a slidable plate carrying an incline, a shoul-

der on the frame adapted to contact with said incline, means to adjust said plate toward and from the cutter in a direction parallel with the axis of rotation of the cutter whereby said incline and coöperating shoulder will produce a simultaneous movement at right angles to said axis and maintain the edge of the work-rest parallel to the operative edge of the cutter, and work-centering devices carried by said slidable plate, substantially as described.

2. In a machine for concaving the heel top lift of a shoe or boot the doubly-concaved heel-rest and the rocker-arms thereto pivotally attached, the adjustable shouldered finger-piece having two inclines adapted to contact with the inside edges of the ends J', J' , of said rocker-arms, the intermediate plate N having a slot N' , and means to retain said finger-piece in a fixed location to confine the positions of the rocker-arms substantially as specified.

3. The combination with the plate I , the rocker-arms J , the confining finger-piece restraining said rocker-arms, and the slotted plate N , of the curved slidable plate B , provided at one end with means for the retention of the heel-plate and at the other end with a bifurcation adapted to embrace the circumferential slot in the thumb-nut C , through which said slidable plate is horizontally adjusted to align with the angle of the blade in proximity to the heel-rest as the cutter rotates, substantially as set forth.

4. The slidable plate having a slot for the reception of the finger-piece provided with two inclines, and a slot to receive means for its lateral flexible support, the attached adjustable incline H , arranged to force outwardly said plate and means forming an integral part of the machine-head to abut against said incline and actuate the slidable plate to a position in alignment with the cutting-angle of each of the revolving blades of the cutter when they are in juxtaposition to the heel-rest as specified.

5. In combination with the slidable plate and its coacting accessories the supporting-flanges A' , A' , adapted to guide and confine said plate in its horizontal movement, the projection A^3 , coacting with the incline and the bearing A^2 , forming a fulcrum for the slidable plate substantially as and for the purpose herein set forth.

6. In a heel top-lift breast-concaving machine, the curved slidable plate having a simultaneous compound movement, and means for its adjustment, the adjustable incline imparting lateral movement thereto, the slotted intermediate plate and the duplex inclined finger-piece adjusted therein, the heel-rest plate, the rocker-arms pivoted thereto, and the adjustable extensions connected to the rocker-arms, all forming coöperative parts of said slidable plate, in combination the bearing forming a fulcrum, the supporting-flanges,

the projection intermediate with said flanges coacting with the adjustable incline, the circular implement having a series of integral blades adapted to cut the concave at a pre-
5 determined angle in the heel top lift, and means to impart a rotatory motion to the cutting implement substantially as specified.

Signed by me at Boston, Massachusetts, this
12th day of April, 1901.

JOHN G. BUZZELL.
